(57) **CLAIM**

The ornamental design of fastener assembly, as shown and described.

DESCRIPTION

FIG. 1 is a perspective view showing our new fastener assembly;

FIG. 2 is a exploded perspective view thereof;

FIG. 3 is a top view thereof;

FIG. 4 is a bottom view thereof;

FIG. 5 is a exploded perspective view thereof;

FIG. 6 is a exploded perspective view thereof;

FIG. 7 is a exploded perspective view thereof; and,

FIG. 8 is a exploded perspective view thereof.
